US00D674263S

(12) **United States Design Patent** (10) **Patent No.:** **US D674,263 S**
Aglassinger (45) **Date of Patent:** **** Jan. 15, 2013**

(54) **SAW**

(75) Inventor: **Hans-Peter Aglassinger**, Esslingen (DE)

(73) Assignee: **Robert Bosch GmbH**, Stuttgart, DE
(US)

(**) Term: **14 Years**

(21) Appl. No.: **29/389,358**

(22) Filed: **Apr. 11, 2011**

(30) **Foreign Application Priority Data**

Oct. 15, 2010 (EM) 001768599

(51) **LOC (9) Cl.** **08-03**

(52) **U.S. Cl.** **D8/64**

(58) **Field of Classification Search** D8/61,
D8/62, 64, 65, 68, 70; 30/166.3, 371, 376,
30/377, 392, 393, 394, 519; 74/49, 50; 173/216,
173/217; 83/697, 699.21, 746; 446/145

See application file for complete search history.

(57) **CLAIM**

The ornamental design for a saw, as shown and described.

DESCRIPTION

FIG. 1 is a perspective view of a saw showing my new design; FIG. 2 is right side elevational view showing the design for the saw of FIG. 1;

FIG. 3 is a left side elevational view showing the design for the saw of FIG. 1;

FIG. 4 is a bottom elevational view showing the design for the saw of FIG. 1;

FIG. 5 is a top elevational view showing the design for the saw of FIG. 1;

FIG. 6 is a rear elevational view showing the design for the saw of FIG. 1; and,

FIG. 7 is a front elevational view showing the design for the saw of FIG. 1.

The broken line portions of the saw in FIG. 4 form no part of the claimed design.

1 Claim, 7 Drawing Sheets
